ERNEST R. GODWARD, OF DUNEDIN, NEW ZEALAND.

METHOD OF AND APPARATUS FOR CARBURATION.

1,291,833.

Specification of Letters Patent.

Patented Jan. 21, 1919.

Application filed November 3, 1917. Serial No. 200,142.

To all whom it may concern:

Be it known that I, ERNEST ROBERT GODWARD, a subject of the King of Great Britain, residing at Dunedin, New Zealand, have 5 invented certain new and useful Improvements in Methods of and Apparatus for Carburation, of which the following is a specification.

This invention relates to carburetors; and 10 the invention has reference, more particularly, to a novel and improved construction of vaporizing or homogenizing mixing chamber through which a charge of gasolene or hydrocarbon and air, in rough mechanical mixture, delivered from an ordinary carburetor or primary mixer, is passed; and to a novel method whereby the gasolene content of the charge while, in a partial vacuum 15 is mechanically suspended and picked up in a manner similar to that described in my co-pending application, Serial No. 90,921, filed April 13, 1916, to stretch, expand and evaporate the gasolene or hydrocarbon particles to cause all said particles to be 20 completely absorbed by the air, so that the final product delivered to the internal combustion engine served by the apparatus comprises a substantially dry homogeneous mixture of hydrocarbon vapor and atmospheric air.

25 The principal object of this invention is to provide a novel method and an improved construction of vaporizing or homogenizing mixing chamber, whereby but a short distance of travel of the charge of gasolene and air is required; and at the same time to provide a plurality of vapor passages within the vaporizing or homogenizing mixing chamber which gradually increase in capacity toward their exit or outlet ends, 30 whereby a proper expansion of the charge of gasolene and air during its movement through the same is provided for; and in addition thereto, the said passages are bounded by walls providing a gradually increasing surface area upon which particles of liquid gasolene may lodge and be suspended for subjection to the stretching, expanding and picking up action of the air moving through said passages, to finally 35 effect the complete evaporation of the liquid gasolene of the charge, and its entire absorption by the air to produce a uniform homogeneous mixture of hydrocarbon vapor and air free from liquid particles of liquid gasolene, and therefore substantially dry and of

a comparatively stable character having little or no tendency to condensation.

Another object of the present invention is to so relate the bounding walls of a plurality of passages through the vaporizing or homogenizing mixing chamber, that not only is the gradually increasing cubic capacity of said passages toward their exit ends provided for, but the said walls are gradually brought closer together toward said exit 60 ends of the passages, whereby the air stream flowing therethrough is thinned out and consequently brought into more intimate contact with the mechanically suspended gasolene particles lodged on the wall surfaces, 70 with a view to aiding and hastening the stretching, expansion and evaporation of said gasolene particles until the same are entirely absorbed and unified with the air.

With the above and other objects in view, 75 which will hereinafter appear as the description continues, the invention consists in the method and the features of construction, combination and arrangement of parts, as will be hereinafter more fully described, and 80 then finally particularly pointed out in the appended claims.

An apparatus capable of carrying out the invention is illustrated in the accompanying drawings, in which:—

85 Figure 1 is a vertical longitudinal section through a vaporizing or homogenizing mixing chamber made according to and embodying the principles of the present invention, and showing in connection with its inlet end 90 one form of primary mixer or ordinary carburetor.

Fig. 2 is a horizontal transverse section through the vaporizing or homogenizing mixing chamber adjacent to its exit or discharge end, taken on line 2—2 of Fig. 1 and looking downward.

Fig. 3 is another horizontal transverse section through the vaporizing or homogenizing mixing chamber adjacent to its inlet 100 or intake end, taken on the line 3—3 of Fig. 1, also looking downward.

Fig. 4 is a diagrammatic fragmentary longitudinal vertical section of a portion of said vaporizing or homogenizing mixing 105 chamber, showing one modified means of surface treatment for the walls of its passages to provide for the mechanical suspension of particles of gasolene thereon.

Fig. 5 is a similar view showing another 110

modified means of surface treatment for the passage walls to provide for the mechanical suspension of particles of gasoline thereon.

Throughout the several views, corresponding parts are indicated by the same characters of reference.

Referring more particularly to said drawings, 1 indicates the main casing of one form of carbureter or primary mixer of air and gasoline, the same providing an interior air chamber 2 with which an air intake member 3, having an inlet 4, communicates. Connected with the upper end of said casing 1 is an annular member 5, the inner wall surfaces of which are flared outwardly and oppositely from an intermediate point toward its respective ends, as at 6 and 7, to provide a restricted or Venturi air passage 8. Connected with the lower end of said casing 1 is a closing member 9 provided with a centrally disposed upwardly extending stud or hub 10 having an internally threaded vertical opening extending therethrough. Connected with said stud or hub 10, so as to extend vertically and centrally upward through said air chamber 2 and into said restricted or Venturi air passage 8, is a gasoline feed-jet 11, having an exteriorly threaded extension 12 of reduced diameter which screws through the internally threaded opening of said stud or hub 10. Said feed-jet 11 and its extension 12 are provided with an upwardly extending gasoline duct 13. Connected with the lower free end of said extension 12 of the feed-jet 11 is a gasoline intake fitting 14, with which may be connected a suitable means (not shown) for supplying gasoline to said feed-jet. Also connected with said intake fitting 14 is an internally threaded nipple 15, in which is adjustably arranged a threaded valve-stem 16 having at its upper end a needle valve member 17 which may be carried into closed or adjusted open relation with a valve-seat 18 formed within said gasoline duct 13, to either shut off or regulate the degree of flow of gasoline from the source of supply into and through said feed-jet 11. Slidably arranged upon and over the upper free end of said feed-jet 11 is a sleeve 19, which terminates at its upper end in an inverted conical spreader head 20, normally fitting or resting in closing relation to the restricted portion of the Venturi air passage 8. Said spreader head 20 provides an internal chamber 21 above said feed-jet 11; from which radial ducts or gasoline passages 22 lead outwardly into an annular discharge mouth 23 opening at the periphery of the enlarged circumference of said spreader head into communication with said Venturi air passage 8. Fixed to and depending from the upper wall of said spreader head 20 is a centrally disposed, tapered valve member 24 which extends downwardly into the upper end of said gasoline

duct 13 of said feed-jet 11. A compression spring 25 engages the upper end of said spreader head 20 to normally thrust the same downward into normal closing relation to the Venturi air passage 8, the downward movement of the spreader head being limited by its engagement with the inclined wall surface 7 of said passage. The devices above described combine to provide one form of primary carbureter or mixing device adapted to deliver to my improved vaporizing or homogenizing mixing chamber a rough mechanical admixture of gasoline and air for further treatment within the same to convert the admixture into a substantially dry uniform homogeneous mixture of hydrocarbon vapor and air. I have described and shown this form of primary carbureter or mixing device, merely to provide a clear understanding of the use and operation of my improved vaporizing or homogenizing mixing chamber; hence I do not limit my invention in any way with reference to the structure of such primary carbureter or mixing device, since any well known construction of carbureter now on the market, which produces a mechanical admixture of gasoline and air, may be employed with my vaporizing or homogenizing mixing chamber in place of the structure above described.

The construction of vaporizing or homogenizing mixing chamber which comprises the essentially novel features of the present invention consists, in the embodiments shown, of an outer casing 26 of inverted truncated conical shape, being of comparatively small diameter at its intake or inlet end and gradually increasing in diameter and circumference toward its enlarged outlet or discharge end. The intake or inlet end of said casing 26 is secured in positive connection with the discharge end of said primary carbureter or mixing device, in communication with the Venturi air passage 8 of the latter. Connected with the discharge end of said casing 26, in any suitable manner, is a cover-member or dome 27, which is provided with a suitable outlet opening 28 adapted to be fitted to and to be suitably connected with the intake manifold or induction pipes leading to the cylinders of the internal combustion engine to be served by the apparatus. Arranged within said casing 26 is a plurality of hollow inverted truncated main conical members 29, the same being nested one within another to provide a plurality of directly extending passages 30 between the walls thereof. The pitch or inclination of the several conical members vary slightly relative to one another, so that the relative distance intervening between the walls thereof at their small intake ends is greater than the distance intervening between the walls thereof at their enlarged outlet ends, consequently

providing the passages 30 with a gradually converging shape in longitudinal cross section toward such outlet ends. Since, however, the said conical members 29 are increased in diameter and circumference toward their outlet ends to a substantial degree, the cross sectional area of the annular passages 30 is gradually increased toward said outlet ends notwithstanding the longitudinally converging conformation of the same above mentioned.

In addition to the nested main conical members 29, I also preferably provide a plurality of intermediate half-length conical members 31, which extend downwardly through the passages 30, for about half the length of the latter, thus again sub-dividing the upper ends of said passages 30 into still narrower annular passages 30^a, so that not only is the gasolene-charged air stream passing therethrough still further thinned out, but a great increase in area of bounding wall surface is provided for catching and mechanically suspending liquid particles of liquid gasolene for the purpose of subjecting the same to the stretching, expanding and evaporating steps necessary to their complete and final absorption and unification with the air. By this means also the annular spaces between the conical and half-length conical members are further narrowed down to a desired degree. The group of conical members and half-conical members is completed by an inner complete conical member 32, the downwardly directed apex 33 of which is centrally alined above the longitudinal axis of the feed-jet 11 and associated parts of the primary carbureter, and as thus located may provide an abutment or base from which the compression spring 25 may exert its tension upon said spreader-head 20 and the tapered valve member 24 connected therewith. The upper end of said inner complete conical member 32 is preferably provided with an upwardly extending outwardly flared annular flange 34, which projects over the outlet ends of the innermost passages 30^a to provide a slight obstruction to the direct pull of the vacuum therethrough, so that the influence of the partial vacuum induced within the device will act more directly and with greater ease within the outermost passages 30^a, thus tending to assure the sub-division of the gasolene-charged air stream more or less equally throughout all of the said passages. The upper end of said complete conical member 32 is closed by a suitably formed top wall 35.

60 The several conical members are secured together in their mutually spaced and nested relation by suitable spacing and fastening means 36, which may, for example, comprise portions of solder so associated with said conical members as to both secure

the same together in fixed relation and space the same one from another.

In operation, the process of carburation commences within the primary carbureter or mixing device, the induction stroke of the 70 internal combustion engine creating a partial vacuum within the whole apparatus, and thereby causing the spreader-head 20 to rise upon the feed-jet 11 and move upwardly into the outwardly flared upper portion of 75 the Venturi air passage 8, whereupon an air passage is opened between the periphery of the spreader-head 20 and the walls of said Venturi air passage proportionate to the amount of upward movement of said 80 spreader-head 20; and since the tapered valve member 24 moves with the spreader-head, the same also provides an opening of the feed-jet 11 more or less proportionate to the opening of the Venturi air passage 8. 85 The incoming air passes through the opened air passage 8 at the periphery of the spreader-head 20, and the gasolene being sucked up out of the feed-jet 11 is directed through the radial openings 22 into the annular discharge mouth 23, where it is engaged by the inrushing air, so that particles of the liquid gasolene are picked up or entrained in the air stream, combining therewith in the form of a rough admixture of 90 gasolene and air, which is discharged from the air passage 8 into the inlet end of the vaporizing or homogenizing mixing chamber.

The mixture thus caused to enter the 100 lower end of the vaporizing or homogenizing mixing chamber immediately divides itself by entering the several passages 30, and, later on, the passages 30^a between the several conical members, and since the passages increase in capacity toward their outlet ends, 105 the mixture moves slower and slower and consequently expands as it flows through said passages toward the exit ends thereof. The lighter particles of gasolene are quickly 110 absorbed by the air and carried onwardly therewith, while the heavier particles are suspended in the air, still in liquid form, so that as the mixture slows up and expands during its onward movement through the 115 passages, gravity tends to arrest the said heavier particles of gasolene, which, consequently, are caused to lodge on the adjacent wall surfaces of the passages, and are there mechanically suspended, as it were, in the 120 presence of or in contact with the continuously moving air current. This deposit of the heavier gasolene particles is kept in onward creeping movement upon the wall surfaces of the conical members by the friction 125 of the air streams; and since the surface area of said walls is constantly increasing toward the upper enlarged ends of said conical members, it follows that said heavier gasolene particles are caused to spread or 130

thin out on said wall surfaces, being thereby stretched and expanded, said stretching and expanding thereof being due also to the partial vacuum within the passages, as well 5 as to the frictional action of the air thereon. As thus stretched and expanded, the heavier liquid particles of gasoline are so thinned out as to be easily vaporized and thereupon taken up or absorbed by the passing current 10 of air, so as to be homogeneously unified therewith. This action continues throughout the passages 30 and 30^a until at the time of discharge from the said passages a substantially dry and stable homogeneous mixture 15 of hydrocarbon vapor and air, rendering an exceedingly efficient combustible or explosive mixture, is ready for delivery to the engine cylinders.

Since said passages become narrower, due 20 to the converging of the walls of the nested conical members toward their outlet ends, the air streams passing therethrough are gradually thinned out, and are thus brought into more direct and intimate contact with 25 the heavier gasoline particles spread or stretched on the adjacent wall surfaces in thin films, and said films become thinner and thinner toward the end of said passages because of the constantly increasing area of 30 the surfaces supporting the same, so that evaporation of the gasoline becomes constantly more rapid whereby the same is finally and completely absorbed into the air. Since evaporation of the gasoline is 35 very rapid, and since evaporation is always accompanied by a lowering of temperature, the atmospheric air delivered to the apparatus may be heated by the waste heat from the exhaust manifold of the engine, if desired, thus using such waste heat units to 40 compensate for the temperature losses due to evaporation, and thereby tending to keep temperature conditions normal within the vaporizing or homogenizing mixing chamber.

45 Referring now to Fig. 4 of the drawings, I have shown therein the conical members of the vaporizing or homogenizing mixing chamber lined with gauze or mesh 37 which provides a roughened surface upon which the 50 heavier particles of gasoline may lodge and be suspended for the stretching, expanding and evaporating action above mentioned. In Fig. 5, I have illustrated another method of treating the surfaces of the conical members for the same purpose, this treatment 55 comprising a roughening of the surfaces by serrating the same with small teeth 38. It will be understood, however, that the degree of roughness imparted to the surfaces of 60 said conical members is subject to a wide variation, according to the conditions of use, and with fuel oils such as good grade gasoline the wall surfaces may be comparatively smooth, as indicated in the main figures of the drawings. I do not wish to

be understood as limiting my invention, in its broader aspects, to the use of any particular surface treatment of the walls of the conical members, except as defined in the claims. 70

It will also be clear, that the number of conical members, and their dimensions, are subject to much change and modification, without departing from the scope of my invention as defined by the claims. 75

Having thus described my present invention, what I claim and desire to protect by Letters Patent is:—

1. In a carbureting apparatus, a vaporizing or homogenizing mixing chamber 80 comprising a plurality of nested, inverted conical or pyramidal members providing direct passages to receive at their inlet ends a rough admixture of hydrocarbon and air to travel therethrough and to be converted 85 into a substantially dry, homogeneous mixture during such travel, said passages increasing in circumference and capacity from their inlet toward their outlet ends.

2. In a carbureting apparatus, a vaporizing or homogenizing mixing chamber comprising an outer inverted truncated conical shell, an inner complete inverted conical shell, and a plurality of nested inverted truncated conical members providing 95 a plurality of direct annular passages to receive at their inlet ends a rough admixture of hydrocarbon and air to travel therethrough and to be converted into a substantially dry, homogeneous mixture during such 100 travel, said passages increasing in circumference and capacity from their inlet toward their outlet ends.

3. In a carbureting apparatus, a vaporizing or homogenizing mixing chamber comprising a plurality of relatively spaced inverted conical members providing a plurality of intermediate passages bounded by walls of constantly increasing surface area 105 from the inlet toward the outlet ends thereof, said passages thus formed constantly increasing in capacity toward their outlet ends and designed to receive at their inlet ends a rough admixture of hydrocarbon and air to travel therethrough and to be converted 110 into a substantially dry, homogeneous mixture during such travel.

4. In a carbureting apparatus, a vaporizing or homogenizing mixing chamber comprising a plurality of relatively spaced 120 nested inverted conical members providing a plurality of intermediate direct annular passages to receive at their inlet ends a rough admixture of gasoline and air, and to be converted into a substantially dry, 125 homogeneous mixture during such travel, said passages increasing in circumference and capacity from their inlet toward their outlet ends, the walls of said conical members converging toward their enlarged ends 130

to constantly narrow the width of said annular passages toward their outlet ends.

5. In a carbureting apparatus, a vaporizing or homogenizing mixing chamber comprising a hollow body having an inlet end and enlarging therefrom toward its outlet end, and means subdividing the interior of said hollow body into a plurality of direct passages of narrow cross-section 10 in one dimension but widening out in the other dimension adapted to receive at their inlet ends a rough admixture of air and gasolene to be drawn therethrough and to be converted into a substantially dry, homogeneous 15 mixture during its travel, said passages increasing in capacity toward the outlet ends and bounded by contiguous walls of constantly increasing surface area.
6. In a carbureting apparatus, a vaporizing or homogenizing chamber comprising a hollow body having an inlet end and enlarging therefrom toward its outlet end, and means sub-dividing the interior of said hollow body into a plurality of direct 20 passages to receive at their inlet ends a rough admixture of air and gasolene to be drawn therethrough and to be converted into a substantially dry, homogeneous mixture during its travel, said passages increasing in 25 capacity toward their outlet ends and bounded by contiguous walls of constantly-increasing surface area; said bounding walls being arranged to converge each toward its next adjacent neighbor to constantly narrow 30 the width of said passages toward their outlet ends.

7. In a carbureting apparatus, a generating chamber comprising a plurality of full-length concentrically separated inverted 40 conical members, and a plurality of short conical members respectively interposed between the enlarged ends of said full-length conical members; said full-length and short conical members providing a plurality of 45 direct annular passages increasing in circumference and capacity toward their outlet ends, and also providing wall surfaces contiguous to said passages which are constantly increasing in surface area toward 50 the outlet of said passages.

8. In a carbureting apparatus, a generating chamber comprising a plurality of full-length concentrically separated inverted conical members, and a plurality of short 55 conical members respectively interposed between the enlarged ends of said full-length conical members, said full-length and short conical members providing a plurality of direct annular passages increasing in circumference and capacity toward their outlet ends, and also providing wall surfaces contiguous to said passages which are constantly increasing in surface area toward 60 the outlet of said passages, the walls of said 65 full-length and short conical members con-

verging toward their enlarged ends to constantly narrow the width of said annular passages toward their outlet ends.

9. In a carbureting apparatus, a generating chamber adapted to be connected in mutual communication between a primary carbureter and the intake manifold of an internal combustion engine, comprising a plurality of nested and concentrically separated tubular members constantly increasing 70 in diameter from their inlet ends and communicating with said primary carbureter toward their inlet ends and with said intake manifold toward their outlet ends; said tubular members providing direct annular 75 passages increasing in capacity toward their outlet ends and bounded by contiguous walls of constantly increasing area toward said outlet ends, the wall surfaces contiguous to said annular passages being roughened. 85

10. In a carbureting apparatus, a generating chamber adapted to be connected in mutual communication between a primary carbureter and the intake manifold of an internal combustion engine, comprising a plurality of nested and concentrically separated tubular members constantly increasing in diameter from their inlet ends and communicating with said primary carbureter toward their inlet ends and with said intake manifold toward their outlet ends; said tubular members providing direct annular passages increasing in capacity toward their outlet ends and bounded by contiguous walls of constantly increasing area toward said outlet ends, and the said walls of said tubular members being arranged to converge each toward its next adjacent neighbor to constantly narrow the width of said annular 95 passages toward their outlet ends; the wall surfaces contiguous to said annular passages being roughened. 100

11. A method of delaying movement of entrained hydrocarbon particles contained in a mixture of hydrocarbon and air, which comprises passing such mixture in the form of currents, which are permitted to expand in the direction of their progress between closely spaced confining walls providing a progressively increasing surface area in the 110 direction of expansion; causing the liquid hydrocarbon particles to be caught on said walls; and exposing said particles while on said walls to the evaporating action of the air currents, the velocity of said air currents being insufficient to tear the liquid particles from said walls but sufficient to slowly propel and spread out such particles on the increasing surface area of said walls in increasingly attenuated form until entirely absorbed into the currents by evaporation. 115

12. A method of delaying movement of the entrained hydrocarbon particles contained in a mixture of hydrocarbon and air, 120

which comprises passing such mixture through a widening passage of narrow cross-section, the bounding walls of which provide adjacent progressively increasing areas of supporting surface; causing the liquid hydrocarbon particles to be caught on said supporting surfaces in intimate relation to the moving current whereby such particles are propelled and spread out upon said surfaces, by the friction and expansion of said current, in increasingly attenuated form until entirely absorbed into said current by evaporation.

13. A method of carburation which consists in pulling an initially constricted current of roughly mixed air and hydrocarbon through a plurality of passages of narrow cross-section in one direction but which gradually widen out in a transverse direc-

tion; slowing up said current by expansion 20 within said passages to deposit the liquid hydrocarbon particles contained therein upon the contiguous wall surfaces of said passages in intimate relation to the current movement, whereby such particles are propelled and spread out upon said surfaces in the direction of progress of the current movement to increasingly attenuate said particles until the same are entirely absorbed into said current by evaporation. 25

30 In testimony whereof I have hereunto set my hand in presence of two subscribing witnesses.
